UNITED STATES PATENT OFFICE

ARCHIBALD HALL-BROWN, OF PURLEY, AND EDWIN WALTER JONES, OF LINCOLN, ENGLAND, ASSIGNEES TO THE BABCOCK & WILCOX COMPANY, OF BAYONNE, NEW JERSEY, A CORPORATION OF NEW JERSEY

AIRSHIP MOORING MAST GEAR

Original application filed November 26, 1927, Serial No. 235,850. Divided and this application filed May 12, 1930. Serial No. 451,609.

This application is a division of our co-pending application, Serial No. 235,850.

The invention relates to an improvement in airship mooring masts and will be best understood from the following description and the annexed drawing, in which the single figure is a vertical section through a tower head and mooring mast showing our invention.

10 The outer tube 1 of the mooring mast is supported in gimbals 2 mounted in known manner in a frame 3 which is rigidly connected to the tower structure 4. The inner tube 5 which is provided with a piston 6, 15 is movably mounted in the tube 1, which thus forms a cylinder cooperating with the piston. The upper or outer end of the tube 5 is provided with the usual cup 7 to receive the nose of an airship, and is provided 20 at its inner or lower end with an extension or tail rod 8 passing through a gland or stuffing box 9 and having at its lower end a cone shaped spigot 10 adapted to be received in a socket member 11. The socket 25 member is in the form of a piston which may be raised or lowered by fluid pressure such as air supplied at two different pressures from the reservoirs 12 and 13, in the manner described in our aforesaid copending application.

The main haul rope 14 passes down through the hollow piston 5 and over a pulley 15 supported in a bracket at the lower end of the mast. The rope then passes 35 around pulleys 16 on the gimbal frames, and thence to the ground. Suitable connections indicated at 17 are adapted to conduct fluid pressure to the cylinder formed by the tube 1, controls for all of the fluid pressure lines being situated in the housing 18.

40 Centering ropes, one of which is shown at 19, are secured to the mast, running over pulleys 20 on the tower and pulleys 21 on the mast, both of these pulleys being 45 mounted on both horizontal and vertical axes, as shown. The pulleys 21 are mounted in a crosshead 22, slidably mounted on the tail rod 8, and the ends of the centering ropes are secured to the mast proper as indicated at 23.

55 Mounted on the mast are one or more cylinders 24 containing pistons 25 adapted to engage the crosshead 22 preferably adjacent one of the pulleys 21. The cylinder 24 is disposed in this form beneath the cylinder formed by the tube 1, and is vertically disposed as shown, its upper end being connected by a pipe 26 to the cylinder 1 in such a position that the port at the upper end of the pipe 26 is uncovered when the piston 6 60 is in its lowermost position, as shown in the drawing. By this arrangement, when the port at the upper end of the pipe 26 is uncovered, the fluid in the cylinder 1 passes into the cylinder 24 and thus operates the 65 piston 25 to force the crosshead 22 longitudinally of the tail rod and thus automatically center the mast. On the upward movement of the piston 6 the fluid in the cylinder 24 may exhaust through the pipe 70 26 back into the cylinder 1.

75 While the cylinders 24 are shown as being supplied with fluid from the tube 1, through the pipes 26, nevertheless we may find it desirable under certain conditions to 75 operate the pistons in these cylinders by fluid from some other source, so that the cylinder 24 may be operated independently of the operation of the piston 6.

80 We claim:

1. An airship mooring mast comprising a vertically disposed cylinder and a piston movably mounted therein, means on the piston rod projecting from the cylinder and adapted to receive a part on an airship, fluid pressure means adapted to exert pressure above said piston, means to center said mast, and means operable upon movement of said piston to actuate said centering means.

85 2. An airship mooring mast comprising a vertically disposed cylinder and a piston movably mounted therein, means on the piston rod projecting from the cylinder and adapted to receive a part on an airship, fluid pressure means adapted to exert pressure above said piston, a centering rope secured to said mast, a pulley slidably mounted on said mast and engaging said rope, and means to slide said pulley on the mast and controlled by movement of said piston.

3. An airship mooring mast comprising a vertically disposed cylinder and a piston movably mounted therein, means on the piston rod projecting from the cylinder and adapted to receive a part on an airship, fluid pressure means adapted to exert pressure above said piston, a centering rope secured to said mast, a pulley slidably mounted on said mast and engaging said rope, a piston adapted to move parallel to said mast and to slide said pulley thereon, a cylinder on said mast and receiving said piston, and fluid pressure means to operate said piston.
4. An airship mooring mast comprising a vertically disposed cylinder and a piston movably mounted therein, means on the piston rod projecting from the cylinder and adapted to receive a part on an airship, fluid pressure means adapted to exert pressure above said piston, a centering rope secured to said mast, a pulley slidably mounted on said mast and engaging said rope, a piston adapted to move parallel to said mast and to slide said pulley thereon, a cylinder on said mast and receiving said piston, and fluid pressure means to operate said piston, said fluid pressure means being operable upon movement of said first-named piston.
5. An airship mooring mast comprising a vertically disposed cylinder and a piston movably mounted therein, means on the piston rod projecting from the cylinder and adapted to receive a part on an airship, fluid pressure means adapted to exert pressure above said piston, a centering rope secured to said mast, a pulley slidably mounted on said mast and engaging said rope, a piston adapted to move parallel to said mast and to slide said pulley thereon, a cylinder on said mast and receiving said piston, fluid pressure means to operate said piston, and a pipe connecting the upper part of said second cylinder with said first-named cylinder at a point above the lowest position occupied by the piston in said first-named cylinder.

ARCHIBALD HALL-BROWN.
